UNITED STATES PATENT OFFICE.

HERMAN FRANK, OF CHICAGO, ILLINOIS, ASSIGNOR OF ONE-HALF TO JULIUS F. RUTZ,
OF CHICAGO, ILLINOIS.

FLASH-IGNITER FOR GAS-BURNERS.

1,240,835.

Specification of Letters Patent. Patented Sept. 25, 1917.

Application filed December 26, 1916. Serial No. 138,838.

To all whom it may concern:

Be it known that I, HERMAN FRANK, a citizen of the United States, and resident of Chicago, in the county of Cook and State 5 of Illinois, have invented certain new and useful Improvements in Flash-Igniters for Gas-Burners; and I do hereby declare that the following is a full, clear, and exact description thereof.

10 My invention refers to lighters for gas stoves and has for its object to provide a single lighter so arranged that it can be selectively adjusted to ignite any one of a series of gas stove burners.

15 Another object of my invention is to provide a structure of the above referred to character so arranged that the lighter can be selectively moved to aline a firing charge with a burner and a means for alinement is 20 arranged to control a gas supply.

A further object of my invention is to provide a firing head which is arranged to shield a pilot light and at the same time to supply the necessary air for the gas mixture, and also to provide a fire aperture 25 whereby the flash jet is discharged through the head.

30 A further object of my invention is to provide a swivel joint for the lighter containing a flash mechanism and a common means for controlling the flash and for directing the alinement of the lighter to a particular burner.

35 With the above objects in view the invention constitutes any constructed combination of mechanic elements as exemplified in the drawing and hereinafter described.

In the drawings:

40 Figure 1 represents a side elevation of a lighter or flash igniter for gas burner embodying features of my invention with parts broken away to more clearly illustrate certain details of structures.

Fig. 2 an enlarged detailed sectional elevation of the controlling flash mechanism.

Fig. 3 is an end view of the lighter head.

Fig. 4 a bottom view of the same.

Fig. 5 a diagrammatic plan view of a group of gas stove burners associated with 50 a flash igniter embodying the features of my invention the igniter being in communication with the gas stove main supply pipe and adapted to swing upon a swivel joint as indicated in dotted line so as to discharge a

jet within the field of any one of the group 55 of burners.

Fig. 6 a sectional elevation of a form of hollow firing head, the section being indicated by line 6—6 of Fig. 7.

Fig. 7 a plan view of the same with parts 60 broken away, but in section to illustrate structural features.

Referring by characters to the drawing A, represents the "header" or main supply gas pipe to the stove into which is tapped 65 or otherwise secured a channeled coupling member. The coupling member has screw threaded therein the shank of a valve shell 1, which shell is provided with a vertical disposed tapered bore for the reception of a 70 hollow valve plug 2, the same forming a swivel or ground joint connection with relation to the shell.

The valve plug is provided with an annular channel 3, in constant connection with 75 a duct 3', with which the shell is provided, and said duct is in communication with the channeled coupling member.

Gas is admitted to a chamber 3''' formed in the hollow valve plug, through a port 3'' 80 which communicates with the channel 3. A partition above this chamber 3''' is formed with a discharge port 6, which port is controlled by the tapered end of a valve stem 9, that projects beyond the upper portion of 85 the valve plug and terminates with a head 9'. The valve stem is reciprocally mounted within a thimble 8 which thimble is in a screw threaded union with the valve plug and extends into a gas chamber 2''' formed in the 90 upper portion of the valve plug.

The valve stem 9 is held to its seat 6 by a coil spring 10 which surrounds the stem and is compressed between the upper end of the sleeve 8 and a pin 8' that is carried by said stem, the pin being guided in slots that extend through the walls of the thimble 8 at its lower end.

The shank portion of the valve shell 1 is provided with a by-pass channel 4 which 100 communicates with the duct 3', and is controlled or regulated by a screw plug 12 and a continuation 4' of the by-pass channel 4 extends into the bore of the valve shell 1 and communicates with an annular recess 5 105 that is formed in the valve plug above the valve-controlled port 6. This annular recess in turn is provided with an aperture 5'

which communicates with the gas chamber 2''''. Thus it will be seen that a constant restricted flow of gas is supplied from the "header" A to said gas chamber irrespective of the position of the valve plug 2. The gas chamber 2''' is also provided with a discharge port 7 that communicates with a threaded boss 7' which constitutes a part of the valve plug.

10 The lower end of the chamber 3''' is closed by a plug 2' which plug is in threaded union with the lower end of the valve plug, said end being extended below the shell. The plug 2' is formed with a head or flange terminal, and said flange constitutes a seat for one end of a coiled spring 10' which surrounds the valve plug with its other end in the engagement with a valve shell, whereby the tapered valve plug is held to its seat and wear is taken up automatically.

15 In order to lift the tapered end of the valve stem from its seat, I provide a lever arm 11, which lever arm is fulcrumed to an ear 2'' that projects from the upper portion 25 of the valve shell. The short arm of this lever 11 is bifurcated and projects under the head of the valve stem.

20 One end of a supply tube 13 is in threaded union with the boss 7' of the valve plug and 35 the outer free end of the tube is in threaded union with a boss that constitutes a part of the hollow firing head 14. The inner end of the firing head boss is formed with a nipple having a restricted gas passage 15 therein.

25 This gas passage is alined with the circular portion 16 of a key-hole shaped fire port, formed in the outer wall of the head. The bottom of the firing head is provided with an air intake slot 17' and the opposite side 40 walls of the said firing head are provided with a series of vent ports 17, whereby combustion is maintained within the head. Thus it will be understood that the single firing head is arranged to maintain a constant 45 pilot light at the point of discharge of the passage 15, which pilot light is protected against cross current of air that would otherwise tend to snuff out said light.

30 From the foregoing description it will be observed that, irrespective of the position of the fire head, a constant pilot light is maintained therein, by means of a restricted quantity of gas which is caused to travel through the by-pass channels 4 and 4' and 55 from thence through the gas chamber 2''' to the port 7 and supply tube 13. By arranging the fire head on the free end of a short tube, at the forward portion of the stove, it will be observed that said firing 60 head is clear of obstruction, so that it can be swung to any selected position as indicated in the diagram Fig. 5, to ignite any one of the group of burners B, or what is termed the simmering burner, which is 65 usually positioned within the center field of

the group of burners. Another advantage of my arrangement and positioning of the lighter is that the simmering burner will not form an obstruction when a burner is to be ignited, which obstruction in practice has been found to exist, where a fixed flash igniter is used. It is apparent that when a burner is to be lighted the operator simply grasps the lever 11 and with one motion the tube carrying the fire head can be swung horizontally, to aline it with the burner to be ignited. When so positioned the operator simply depresses the handle of the lever 11, whereby the valve stem 9, will in opposition to its spring, lift from the flash port 6, thereby permitting a full flow of gas to enter through said port and the various channels, resulting in the pilot light developing a thin flame jet, which will be discharged upon the gas stove burner.

70 Hence a common controlling means is provided whereby the fire head is adjusted to any position desired and a flame is caused to be discharged within the field of the burner.

75 While I have shown and described a specific swivel valve, which constitutes the hinge connection for the flash igniter, it is manifested that I may without departing from the spirit of invention, vary the details of structure within the knowledge, of 80 whom are termed, skilled mechanics.

85 Referring particularly to Figs. 6 and 7 of the drawings showing my preferred form of hollow firing head, 18 represents a circular cup like shell the bottom of which is provided with a series of air intake openings 19, and the upper edge of the shell is cut away at intervals to form spring lips 20 which lips are offset. By offsetting the lips 20 the cut away portions of the side walls of the shell constitute vent apertures 20', the upper edge of the cup like shell is closed by a removable cap piece 21 having a down turned flange 21' which is circular in form and engages the lips 20.

90 By this arrangement it will be seen that the gas fumes can be vented through the openings 20'.

95 The side walls of the shell are provided with a single circular fire port 22, and opposite its firing port, this shell side walls are formed with an opening 23 whereby a coupling connecting is effected between the shell and tube 13.

100 This coupling connection comprises a nipple 24 having a reduced end 25 which projects through the aperture 23 and terminates at the center point of the shell, the said nipple being provided with a gas passage 15'. The reduced end of the nipple is threaded 105 at its shank for the reception of a clamping nut 25' and the outer end of the nipple is formed with an internally threaded ferrule portion 26, which abuts the outer wall of the shell, the same being bound between a 110

shouldered portion of the ferrule and the nut. The tube as shown is in threaded union with the nipple.

By the construction just described it will be apparent that, owing to the fact that only one fire port is employed, there is no opportunity for cross currents of air to snuff out the pilot light. Attention is also directed to the fact that in this form of firing head perfect combustion is effected by the introduction of air through the bottom of the shell in an upward direction and the venting of said shell at its top, which vents are in turn protected against outward blast of air, or back currents by the down turned flange 21'.

I am aware that the prior art discloses broadly some type of swiveled flash igniters, but so far as I am aware these igniters do not provide means for incasing a constantly burning pilot light, nor do they show an auxiliary valve at their swivel point provided with a controlling handle which will, when moved in a horizontal direction, adjust the flash igniter to light a particular burner, and when moved in a vertical direction increase the supply of gas to the restricted constantly burning pilot light to thus cause a jet of flame to enter the field of the burner to be ignited. Attention is further directed to the fact that igniter torches of the fixed type must necessarily be provided with a plurality of firing ports that are formed in the shell or incasing head of the pilot light. Hence owing to the fact of this multiplicity of firing ports, cross currents of air will snuff out the pilot and this result has been demonstrated in practice.

By employing a construction wherein a single port is employed in combination with a swivel member the cross currents of air will not have a snuffing effect upon the pilot light, and furthermore, owing to the incasement of the pilot light as described, even though the arm carrying it is shifted rapidly, the tendency of the pilot to blow out is off-set, as the only current of air which can possibly travel through the casing then is from the bottom to the top of the same or through it in a horizontal direction, and the gas discharge which supplies the restricted pilot light is arranged diametrically opposite the firing port in the wall head or shell so that the current of air entering this firing port will be neutralized by said gas discharge.

What is claimed:

1. The combination of a gas stove having a series of burners, a flash igniter therefor the same comprising a swiveled supply tube, a hollow head carried at the free end of the tube provided with vents in its bottom and side walls and a single horizontally disposed firing port, a horizontal nipple in communication with the free end of the tube

and extending into the head in axial alignment with the firing port thereof, means for supplying a constant restricted quantity of gas to the nipple, an auxiliary valve mounted within the swiveled connection of the igniter, and a handle for the valve adapted to shift the flash igniter to selective position when moved horizontally and to increase the supply of gas to the nipple when moved vertically. 75

2. The combination with a gas stove having a series of burners, a flash igniter therefor comprising a swiveled supply tube, a firing head on the free end of the tube, means for supplying a constant restricted quantity of gas to the firing head, an auxiliary valve mounted within the swiveled connection of the igniter, and a handle for the auxiliary valve, said handle shifting the flash igniter to selective positions when moved horizontally and increasing the supply of gas to the firing head when moved vertically. 80

3. A flash igniter head for swiveled burner igniters comprising a cup-like shell 90 having a series of air inlet openings in its bottom, a plurality of outlet vents in the side wall adjacent the upper edge and a single firing port in the side wall; a gas nipple having a restricted opening extending through the side wall opposite the firing port and in alignment therewith, a cap closure for the top of the shell having down turned flanges adapted to shield the outlet vents and lips extending from the body of the shell for supporting the cap. 95

4. A flash igniter head for swiveled burner igniters comprising a cup-like shell having a series of air inlet openings in its bottom and a single firing port in the side wall, the upper edge of the side walls being slit at intervals to form spring lips which are offset outwardly to provide outlet vents, a removable cap piece having down turned flanges to shield the outlet vents, said spring lips engaging the flanges of the cap to hold the same in position, and a gas nipple having a restricted opening extending through the side wall opposite the firing port and in alignment therewith. 105 110

5. A flash igniter head for swiveled burner igniters comprising a cup-like shell having a series of air inlet openings in its bottom, the upper edge of the side wall being slit at intervals to form spring lips which are offset outwardly to provide outlet vents, the side wall of said shell also having a pair of aligned openings, one forming a firing port, a coupling member having a reduced and shouldered end to form a nipple, said nipple being disposed through the other of the last mentioned pair of openings and in alignment with the firing port, said shoulder abutting the outer side of the side wall of the shell, a clamping nut on the reduced end 120 125 130

of said member for clamping the side wall of the shell between it and the shoulder of the member, a fuel supply pipe connected with the outer end of the coupling member, 5 and a removable cap piece having down turned flanges to shield the outlet vents, said spring lips engaging the flanges of the cap to hold the same in position.

6. The combination with a firing member, 10 of a control valve therefor comprising a valve shell having a bore therethrough, a substantially cylindrical tubular valve plug disposed for rotation in the bore of the shell, the outer wall of the plug having a pair of 15 longitudinally spaced annular channels, each communicating with the interior of the plug by means of a opening through the wall thereof, said plug also having an outlet adjacent one end communicating with the firing member, said shell having a main gas 20 passage way communicating with one of the channels and a by-pass from the main passage way to the other channel, an apertured partition wall in the tubular plug between 25 the two openings from the channels, the aperture therein forming a valve seat, a closure in the end of the plug remote from the outlet thereof, a valve stem in the opposite end of the plug and carrying a valve head 30 for coaction with said seat, and an operating handle for the valve stem.

7. The combination of a plurality of gas burners and a flash igniter therefor comprising a manually controlled swiveled igniting tube movable selectively into coöperative relation with individual burners to ignite the gas therefrom, a connection between said igniting tube and a source of gas supply, 35 means for supplying a constant restricted

supply of gas to said igniting tube, a valve 40 controlling said connection and normally restricting the supply of gas independently of any position assumed by the swiveled tube, manually operated means capable of being operated during movement of the swiveled 45 igniting tube and after it has been selectively adjusted, for opening said valve to increase the supply of gas to said igniting tube and means for returning said valve to its closed position as soon as said valve opening means 50 is released irrespective of any position assumed by the igniting tube.

8. The combination of a plurality of gas burners and a flash igniter therefor, comprising a manually controlled swiveled igniting tube movable selectively into coöperative relation with individual burners to ignite the gas therefrom, a connection between said igniting tube and a source of gas supply, 55 means for supplying a constant restricted 60 supply of gas to said igniting tube, a valve controlling said connection and normally restricting the supply of gas independently of any position assumed by the swiveled tube, a handle for selectively adjusting the igniting tube, and for opening said valve to increase the supply of gas to said igniting tube after it has been selectively adjusted and a 65 spring for returning said valve to its closed position as soon as said opening means is 70 released, irrespective of any position assumed by the igniting tube.

In testimony that I claim the foregoing I have hereunto set my hand at Milwaukee, in the county of Milwaukee and State of 75 Wisconsin.

HERMAN FRANK.
